PROCESS FOR CONDITIONING YARN
ON BOBBINS, ETC.

Vasser Woolley, Atlanta, Ga., assignor to Seydel-Woolley & Company, Atlanta, Ga., a copartnership

Application March 17, 1941, Serial No. 383,885

3 Claims. (Cl. 8—155)

This invention relates to machines and methods or processes of applying liquid to yarn while in the form of packages such as on bobbins, cones, spools or cops especially for setting the twist in the yarn.

It has been customary to apply the liquid to such yarn while the bobbins are travelling on a conveyor belt, or chain or through a revolving cylinder. A great difficulty in all of such machines has been the excessive wear on the moving parts which operate without lubrication under the spray of water and penetrant. In some cases steam is applied but this is injurious to the bobbins and a steam room takes up a great deal of space.

This invention is the result of extensive study of the conditions involved in this work. One object is to provide a satisfactory method of uniformly applying the proper amount of liquid.

A special object is to provide a simple and inexpensive machine in which the packages require no moving devices to carry them through.

Another object is to provide a compact and inexpensive machine.

Accordingly one form of machine embodies a casing having a vertical series of inclined baffles arranged so that packages dropped on the upper baffle roll or spin down on to the next and thence over a grille and out of the machine. Sprays of the desired liquid are blown or otherwise forced from opposite sides of the machine on to the moving packages. Excess of liquid is thrown off by the impact upon the baffles and screen. The used liquid passes through the grille and back into the supply tank from which it is again forced from the spray heads to be used again until exhausted. This used liquid is preferably filtered before passing back into the supply tank.

Another form of machine employs a series of inclined grill sections down which the packages are allowed to fall freely while they are sprayed from at least one side with the desired liquid.

In still a third form the packages are dropped through a hopper into a casing where they are deflected on to an annular platform and as they fall liquid is sprayed laterally from the center so that the rolling and twisting packages are moistened before they reach the platform. This platform may be rotated to assist in ejecting the packages.

Fig. 1 is a front view of the novel parts of one form of machine for carrying out the invention.

Fig. 2 is a vertical sectional view of the same.

Fig. 3 is a vertical sectional view of another form of machine.

Figs. 4 and 5 are vertical and horizontal sectional views respectively of another form of machine.

The casing 5 may be of any suitable material and contains the shelves or baffles 6, 7 and 8 which may be arranged to overlap in a vertical series between the entrance 9 and the outlet 10. The packages 10 will roll or fall from shelf to shelf however even if they do not overlap. A grille 11 is detachably mounted between the baffle 8 and the outlet and serves to deflect the falling packages to the outlet and the container 12.

The treating liquid is forced by a suitable pump and air pressure or other means (not shown) from spray heads or nozzles 14 and 15 arranged respectively opposite the spaces between baffles 6 and 7 and between baffles 7 and 8, respectively. In this way as the packages roll and spin back and forth, the liquid is sprayed upon all sides. As the packages strike against the baffles and the walls of the casing, the excess of liquid is thrown off by the impact so that the yarn is moistened uniformly.

The unabsorbed liquid drains back into the tank 16 preferably through the filter 17.

The filter or screen 17 is preferably detachably mounted in the casing and may be reached through the door 18. The liquid may be drawn from the pipe 19 and forced by a pump or other means (not shown) through the nozzles 14 and 15 as above mentioned.

In the form shown in Fig. 3 there are a series of shelves or baffles 20, 21, 22 and 23 between the inlet 24 and the outlet 25 so that the bobbins or other packages roll, spin and twist from shelf to shelf while they are sprayed laterally from the heads 26 and 27. Part or all of each shelf such as 21, 22 and 23 is perforated so as to allow excess liquid to return to the tank 28 from which it is returned to the spraying means.

In the form shown in Figs. 4 and 5 there is a cylindrical casing 30 with a feed hopper 31 at the top and a tank 32 at the bottom. Inside the casing is a platform 33 which is perforated to allow liquid to pass through. In the center is a spray device having means 34 for spraying liquid laterally around the casing beneath the deflector 35. The pump 36 may be located in the center beneath the spraying device and surrounded by the cylinder 37. The platform 33 may be revolved so as to bring the packages which fall upon it around to the discharge outlet 38 where they are deflected outwardly by the stationary plate 39. A filter 40 may be provided above the tank so as to keep the liquid free of foreign particles.

The successive shelves or plates serve to slow up the packages so that their speed is controlled substantially that due to gravity acting from shelf to shelf rather than acquiring the momentum due to falling from the top to the bottom of the spray chamber.

I claim:

1. The method of conditioning yarn on spools or the like which consists in feeding the spools to a housing, permitting said spools to fall downwardly by gravity along a circuitous path over and between inclined spaced perforated plates whereby for portions of their travel said spools fall free of said plates and subjecting said spools to a continuous spray during their movement along, over and between said plates to saturate thoroughly the yarn on said spools.

2. The method of conditioning yarn on spools or the like which consists in feeding the spools to the top of a vertical housing, permitting said spools to fall downwardly by gravity along a cir-

cuitous path over and between alternately inclined spaced perforated plates whereby for portions of their travel at different intervals said spools fall free of said plates, subjecting said spools to a continuous spray from both sides of said housing during their movement along, over and between said plates to saturate thoroughly the yarn on said spools and finally draining said spools to remove the excess liquid therefrom.

3. The method of conditioning yarn on spools and the like which consists of feeding said spools to the top of a housing, permitting said spools to fall by gravity over a series of plates alternately inclined with a space between said plates whereby said spools are subjected to a tumbling action during their downward movement and subjecting said moving spools to a continuous spray of liquid during their downward travel out of contact with the plates whereby the yarn on said spools becomes thoroughly saturated.

VASSER WOOLLEY.
